UNITED STATES PATENT OFFICE.

CHARLES H. BAKER AND FRANCIS L. BESTOR, OF KNOXVILLE, ASSIGNORS
TO THEMSELVES, AND THOMAS C. CUNNINGHAM, OF SIGOURNEY, IOWA.

BARB-WIRE MACHINE.

SPECIFICATION forming part of Letters Patent No. 323,489, dated August 4, 1885.

Application filed May 13, 1884. (No model.)

To all whom it may concern:

Be it known that we, CHARLES H. BAKER and FRANCIS L. BESTOR, citizens of the United States of America, residing at Knoxville, in the county of Marion and State of Iowa, have invented certain new and useful Improvements in Barb-Wire Machines, of which the following is a specification, reference being had therein to the accompanying drawings.

10 Our invention relates to an improved machine for attaching barbs to fence-wire. The object it has in view is to obtain a machine which will accomplish the result sought with rapidity and certainty; and to that end the 15 invention consists of the novel devices and combination of devices, as will be described and claimed.

Reference will be made to the accompanying drawings, in which Figure 1 is a side elevation, partly in section; Fig. 2, a section on line 1-1 of Fig. 1; Fig. 3, a section on line 2 2 of Fig. 1; Fig. 4, a detail of the mechanism for raising and lowering the fence-wire, and Figs. 5 and 6 details of a modified arrange- 25 ment.

Like letters refer to like parts in each view.

A represents the base of the machine, and B the main driving-shaft. To one end of shaft B is secured an eccentric, C, to which an arm, 30 D, is secured, said arm being connected at its upper end to an arm, E, loosely mounted on a shaft, F, which has bearings in one set of uprights, G, mounted upon base A. Secured to shaft end of arm E is a spring-depressed 35 pawl, H, which engages with a ratchet, I, keyed to outer end of shaft F, to which is also keyed a cog, K.

The parts thus far described are so arranged with respect to each other that upon each revolution of shaft B the cog K is revolved one- 40 third. This cog in its revolution meshes with and imparts motion to a cog, L, mounted upon a shaft, M, which extends the entire length of the machine. Cog L is but one-third the size of cog K, and therefore upon each 45 revolution of shaft B it is revolved once. Cog L meshes with a cog, N, of one-half its size, and which is mounted upon a slotted tube, O, which is supported in the upper ends of up-

rights or standards G. There is a slot, b, 50 formed in each end of the standard G, which extends down to a circular space, in which the tube O is mounted. This tube is also provided with a slot to correspond with slot b, and which extends the entire length of the tube, a 55 similar slot being also formed in the cog N, mounted upon the tube, this arrangement affording a clear passage for the wire to the tube; and, further, each tube is provided upon each end with a wrapping-pin, c. By this 60 arrangement it will be seen that upon each revolution of shaft B this tube is revolved twice and the barb wrapped twice around the fence-wire, which is passed through the slot in said tube. As shown in the drawings, there 65 are a series of these tubes O, and upon the shaft M a series of cogs, L, one for each tube, and all driven by the one connection with the main shaft B. Keyed to shaft B is a cog, P, which passes up through the base A, and 70 meshes with a cog, Q, keyed to a shaft, R, to each outer end of which is secured an eccentric, S, into a slot in each of which a pin, a, of an arm, T, is inserted. The arms T are situated one at each end of the machine, and 75 move in openings formed in the base A, and are provided with openings, through which shafts M R are passed, to insure a steady vertical movement, which is brought about by the eccentrics described, the parts being so 80 arranged that at certain intervals the arms will be lowered to draw the fence-wire into the grooves of tubes O, to allow of the attachment of the barbs, and then raise the same 85 therefrom to allow of its being fed forward, said wire being passed through arms U, mounted upon the upper ends of said arms T.

V are standards mounted at each end of the machine, and upon the upper end of each of which is mounted a sheave, W, over which 90 the fence-wire is passed.

X, Fig. 1, represents suitable table supports or guides arranged upon the frame-work at suitable points to accommodate the barb-wire as it is fed to the wrapping-pins of the rolls O. 95

In Figs. 5, 6 we have shown an arrangement by which a double wire may be used in connection with our mechanism. In this ar-

angement, as shown, there are two tubes O, placed side by side and at a slight angle with respect to each other, each provided with a cog, N, meshing with each other, and one meshing with the cog L, referred to.

The operation will be readily understood. By the arrangement of parts as described, the fence-wire is drawn down into the slots of tubes O, and said tubes are then, through the 10 gearing described, revolved twice, when the arms T are raised, and with them the fence-wire, which is then fed forward and again lowered into the slots of the tubes for the attachment of more barbs.

15 We lay no claim to any special fence-wire or barb-wire feeding mechanism, but desire to use that most advantageous to our machine.

What we claim is—

1. The combination, with a series of slotted 20 wrapping-tubes mounted in stationary bearings, of mechanism for drawing the fence-wires into said tubes and at intervals lifting them therefrom, as set forth.

2. The combination, with a series of slotted 25 wrapping-tubes mounted in stationary bear-

ings and upon the same vertical plane, of mechanism for drawing the fence-wires into said tubes and at intervals lifting them therefrom, as set forth.

3. The combination, with shaft B and eccentric C, mounted thereon, of arms D E, pawl H, and ratchet I, wrapping-tubes O, and intermediate gearing for revolving said tubes, as described.

4. The combination, with slotted wrapping-tubes, shaft B, and shaft R, driven therefrom, of eccentrics S, secured to shaft R, and arms T U, driven from said eccentrics, as set forth.

5. The combination of wrapping-tubes O, arms T, having arms U, and means for driving said parts to attach barbs to the fence-wires, and to insert and withdraw the wires from said tubes, as described.

In testimony whereof we affix our signatures in presence of two witnesses.

CHARLES H. BAKER.
FRANCIS L. BESTOR.
